UNITED STATES PATENT OFFICE.

WLADIMIR KAVAN, OF NEW YORK, N. Y.

BARBER'S POLE.

1,372,954.

Specification of Letters Patent. Patented Mar. 29, 1921.

Application filed September 7, 1920. Serial No. 408,418.

To all whom it may concern:

Be it known that I, WLADIMIR KAVAN, a citizen of Moravia, residing at New York, in the county and State of New York, have 5 invented certain new and useful Improvements in Barbers' Poles, of which the following is a full, clear, and exact specification.

This invention relates to barbers' poles, 10 and has for its object to provide a collapsible pole adapted to be extended or raised when in use and contracted or telescoped when not in use or out of business hours.

The invention contemplates the provision 15 of means for counterbalancing the telescopic upper portion of the pole whereby it may be readily raised and lowered and held in any desired position. Other objects will appear as the description proceeds.

20 The invention will be first hereinafter described in connection with the accompanying drawings, which constitute part of this specification, and then more specifically defined in the claim at the end of the description.

25 In the accompanying drawings, wherein similar reference characters are used to designate corresponding parts throughout the several views:—

30 Figure 1 is an elevation of a barber's pole constructed substantially in accordance with this invention.

Fig. 2 is a central vertical section of the same with the telescopic upper portion 35 raised as in Fig. 1.

Fig. 3 is an elevation of the pole collapsed, and

Fig. 4 is a central vertical section of the pole as shown in Fig. 3.

40 The pole is made in two sections both of which may be constructed of sheet metal or any other suitable material. The upper section 1 is fitted to telescope over the lower section 2 as clearly illustrated in the drawings.

45 To counterbalance the sliding upper section 1 weights 3 are suspended on cords 4 which are passed over sheaves or pulleys 5 suitably journaled on the interior of the lower section 1 near the upper end thereof,

said cords being attached to the interior of 50 the upper section near its lower end as indicated at 6 in Figs. 2 and 4. When the top section 1 is collapsed, as shown in Fig. 4, the cords 4 lie between the inner surface of the upper section 1 and the outer surface of the 55 lower section 2. The cords extend through slots or notches 7 in the upper edge of the lower section and are freely movable therein for allowing the upper section 1 of the pole to be raised and lowered at will. 60

When the upper section of the pole is raised it presents an imposing appearance calculated to attract the attention of customers during business hours, but when collapsed the reduced length of the pole indicates that the shop is closed. The relative dimensions of the sections of the pole may be varied as may be found desirable. While two counterweights 3 are shown arranged at 65 diametrically opposite points in the pole, it 70 will be understood that the number of said weights may be changed without departing from the invention. The construction or equipment of the pole or either of the sections thereof may also be modified without 75 omitting the counterbalanced telescoping feature of the invention.

Having thus described my invention, what I claim as new and desire to secure by Letters Patent of the United States is:— 80

In a barber's pole, the combination with a lower stationary portion, of an upper tubular portion of greater diameter than the lower portion and adapted to telescope around said lower portion for increasing or 85 diminishing the length of the pole, sheaves on the upper edge portion of the stationary part, cords passed over said sheaves and attached at one end to the telescoping part, and weights attached to the other ends of 90 said cords and housed in the stationary portion for counterbalancing said telescoping part, said sheaves and cords being housed by the telescoping portion.

In testimony whereof I have signed my 95 name to this specification.

WLADIMIR KAVAN.
